UNITED STATES PATENT OFFICE.

IRVEN H. WILSEY, OF CHICAGO, ILLINOIS, ASSIGNOR, BY MESNE ASSIGNMENTS, TO WILSEY INCORPORATED, A CORPORATION OF DELAWARE.

METHOD AND APPARATUS FOR CONTROLLING INTERNAL-COMBUSTION ENGINES.

Application filed October 29, 1920. Serial No. 426,329.

To all whom it may concern:

Be it known that I, IRVEN H. WILSEY, a citizen of the United States, residing at Chicago, in the county of Cook and State of Illinois, have invented certain new and useful Improvements in Methods and Apparatus for Controlling Internal-Combustion Engines, of which the following is a specification.

10 My invention relates to control systems for internal combustion engines and more specifically to an improved method and apparatus for automatically providing at all the various combinations of speeds and 15 loads under which such engines are operated, the most desirable mixture for the particular engine in question under the particular conditions of service at that instant.

20 A brief consideration of the different kinds of mixtures required and the conditions under which each mixture should be supplied will facilitate an understanding of my invention. For a maximum of power at any speed the mixture should be rich 25 enough to secure a maximum of energy per unit of mass and should be as cold as possible so that the greatest possible mass of mixture will be drawn into the cylinder on each suction stroke.

30 The most economical mixture from the point of view of fuel consumption and also from the point of view of keeping the cylinders and spark plugs clean and free from carbon, is a relatively weak mixture supplied 35 at a relatively high temperature. This mixture will enable the engine to operate with satisfactory smoothness and sufficient power at moderate loads and speeds.

40 The conditions under which internal combustion engines are operated can be broadly divided into operation at extreme load at any speed; operation at moderate loads, which must necessarily mean slow or moderate speeds since high speeds cannot be 45 attained under load without high power; and idling or operation at practically no load and a relatively low speed. The mixture to be supplied when the engine is idling may be made hot and lean for maximum 50 economy although for a maximum of convenience a fairly hot and fairly rich mixture is desirable as the engine can be throttled down to lower speeds with such a mixture. An apparatus according to my invention 55 can readily be arranged to secure maxi-

mum economy or maximum convenience in idling or any compromise between the two to suit the wishes of the individual user.

There is another possible condition of operation to be encountered when the engine 60 is allowed to race by inexperienced or careless operators. While I prefer not to include this condition as one of the service conditions of the engine, it will be apparent that according to my invention this condition also is provided for.

65 The primary object of my invention is to provide the proper mixture for the engine at all times. I have outlined above the mixtures which are considered most advantageous for the operation of the best internal combustion engines at present on the market, but it will be apparent that the principles of my invention may readily be applied to provide almost any variation of 70 richness or temperature or both to correspond to the needs of the present day engines or of engines requiring mixtures of a radically different nature.

75 Another object of my invention is to provide a unitary and compact device for handling both the intake and the exhaust and for providing for proper heat interchange between the same.

80 Further objects and advantages of my invention will become apparent as the description proceeds.

85 In the accompanying drawings, Figure 1 is a side elevation of a carburetor and intake and exhaust manifolds illustrating the application of my invention to a well known type of internal combustion engine. Figure 2 is a plan view of the exhaust manifold from underneath and partly in section. Fig. 3 is a vertical section through the exhaust 90 manifold. Fig. 4 is a transverse section through the manifold and valve carried thereby. Fig. 5 is a transverse section of the manifold in the plane of the inlet passage. Fig. 6 is a side view of the valve, including the throttle controlled sleeve; and Fig. 7 is a section on the line 7-7 of Fig. 6.

95 In the embodiment of my invention selected for illustration, the exhaust manifold 10 is designed to receive the exhaust from each of the four cylinders of the engine through exhaust ports 12, 14, 16 and 18, and is equipped with downwardly projecting bosses 20 defining short passageways 22 opening into the two inlet ports of the engine. 110

The inlet manifold 24 usually connected directly to the ports of the engine may be clamped against these bosses. In Fig. 1, I have illustrated conventionally a carburetor 26 of any desired type having a throttle 28 adjacent the flange 30 which connects it to the inlet manifold.

According to my invention, the carburetor should be adjusted to deliver a rich mixture of substantially constant richness throughout the entire range of operation except at very slow speeds at which it may be adjusted to get a different mixture if desired. All the mixture from the carburetor is delivered unchanged to the passageways 22 in front of the inlet ports of the engine and the control is accomplished by adding to the mixture thus delivered as it enters the inlet ports, pure air heated to a high temperature. It will be obvious, however, that in its broad aspects my invention is not limited to this method of obtaining the final result desired, which result can also be obtained by diluting the mixture to the desired richness with unheated air and subsequently heating the mixture to the desired temperature.

My improved valve for automatically controlling the dilution of the mixture comprises in this instance a stationary tube 32 clamped in a split cylinder 34 projecting from a cover 36 fastened to the front of the manifold, by means of clamping screws 38. The under surface of the cover is arched (Fig. 4) and cooperates with a gasket 40 clamped in place between the cover and the body of the manifold to define a passage 42. From the passage 42 air may flow through a centrally located aperture 44 (see Fig. 1) in the gasket 40, into a flat chamber 46 formed inside the box-like exhaust manifold, which chamber extends as shown in Fig. 3 from above one inlet port to above the other and provides a large surface exposed to the heat of the exhaust gases and making contact with the air within the chamber to provide ample means for conducting heat from the exhaust gases to the dilution air so as to raise the air to a very high temperature. The heated air enters the passageways 22 through small vertical passages 48 (see Fig. 5) extending downwardly from the extreme corners of the chamber 46.

An inner plunger 50 reciprocates within the tube 32 being urged downwardly by the force of a compression spring 52 housed in the upper end of the tube, and is provided with a port 54 near its upper end and with ports 56 near its lower end, adapted upon elevation of the plunger to move more or less into register with the outlet port 58 leading from the tube into the passageway 42 and with the inlet ports 60 near the lower end of the sleeve. As the chamber 46, passageway 42 and the interior of the plunger 50 are in

communication with the inlet ports by means of passages 48 and 22, the pressure inside the plunger 50 will, unless air is flowing through the plunger, be precisely the same as that in the inlet passages leading to the engine. The development of suction in the inlet passages will therefore permit atmospheric pressure acting on the bottom of the plunger to raise it and move the plunger carried ports more or less into register with the tube ports.

Outside the lower end of the tube I mount an outer sleeve 62 cut down as at 64 to form shoulders engaging a pin 66 so as to limit the rotation of the outer sleeve to about 180°. The outer sleeve is provided with ports 68 adapted to be moved into and out of register with the ports 60 in the tube by rotation of the outer sleeve. Referring to Figs. 6 and 1, it will be seen that the radially projecting arm 70 carried by the outer sleeve 62, and the throttle control arm 72 are connected by a vertical pin 74 extending through the outer ends of both, to which pin the control rod 75 used by the operator for controlling the engine is to be connected. The outer sleeve 62 and plunger 50 may both be held against downward displacement by a single cotter pin 76 passed through apertures adjacent the extreme lower end of tube 32, and the plunger may be prevented from rotating by any suitable means such as a small pin 78 reciprocating with the plunger and projecting into vertical slots 80 cut in the tube 32. The operation of the device is as follows:—

Ports 68 are so arranged as to be moved gradually into register with ports 60 as the throttle is opened so that at all throttle positions except an almost closed throttle more or less dilution would be permitted and with the throttle wide open, a maximum would be possible. With the throttle wide open, however, the operator requires maximum power from the engine. It will be seen that throwing the throttle wide open will permit the pressure in the inlet passages to become practically atmospheric so that plunger 50 will move down to the position shown in Fig. 4 under the action of spring 52 and no dilution will occur. A cold rich mixture is thus automatically delivered to the engine as long as the throttle remains wide open.

Suppose, however, that after accelerating to a moderate speed the operator partly closes the throttle to prevent further acceleration thereby preventing the engine from developing a heavy torque, so that the operation is one at a moderate speed and moderate load. Under such circumstances, the throttle controlled ports 68 will be partly in register with the tube ports 60 and the partial vacuum in the inlet passages caused by partial closure of the throttle will move the plunger ports 56 and 54 partly

into register so that air will flow through the heating chamber 46 and the mixture entering the inlet ports of the engine will be diluted with hot air to produce the lean hot mixture required for economical operation.

When the engine is idling the throttle is completely closed and the ports 68 are completely out of register so that so far as the 10 operation of the ports is concerned, no dilution should occur and a cold rich mixture would be delivered to the engine. Under these conditions, however, the vacuum in the inlet passages is very high and the mass of 15 gas flowing through them is very low to the low speed of the engine and the attenuation of the gas itself by the low pressure. The sleeve 62 may readily be designed so as to fit rather loosely on the tube 32 and permit 20 a leakage which when the suction is high and the volume of flow low, will have a very appreciable effect on the resulting mixture, although it is practically negligible under all other conditions due to the great increase 25 in the volume of flow and the decrease in the suction. It will be seen that for controlling the idling mixture I rely upon an entirely independent function inherent in the design of the parts used, which function 30 may be varied without any appreciable effect except when the engine is idling. For maximum economy the carburetor may be adjusted to supply a constant mixture at all speeds so that the mixture when idling 35 will be rather lean and hot. For users who prefer convenience to economy, however, it will be obvious that the use of any one of the well known types of carburetor capable of increasing the richness of the mixture 40 delivered therefrom at very low rates of flow, will make possible the furnishing of a hot mixture which is nevertheless rich enough to permit the engine to be throttled down to a very low speed.

45 The internal combustion engines employed in present day motor vehicles are of course designed to operate at the necessary speed to drive the car at the maximum speed at which it is intended to be driven without 50 developing forces due to the inertia of the pistons, connecting rods and other movable parts greater than are permissible with safety. With properly designed inlet passages such an engine can also be operated 55 at the maximum speed for which it is intended without developing more than a very slight vacuum in the inlet passages provided the throttle is wide open. Such an engine, however, when not connected to a load is 60 apt to develop a speed with the throttle wide open such that the inertia of the parts will develop forces sufficient to injure or even wreck the engine, and an inexperienced or careless driver may readily injure an engine by thus operating it.

In an engine equipped with my improved control system the strength of spring 52 may be readily designed so that with a wide open throttle the engine can develop the maximum power of which it is capable when connected to the load it is intended to carry, without developing sufficient vacuum to permit any appreciable dilution of the mixture, which dilution would cut down the available power.

Increase in the speed of the engine above this point will, however, increase the vacuum in the inlet passages in proportion to the square of the speed, so that if the throttle is thrown wide open without a load on the engine, as soon as the engine begins to race, plunger 50 will be lifted and may even rise to bring ports 56 completely into register with ports 60. The parts are designed so that with ports 68 partly in register and 80 ports 56 partly in register, dilution will occur sufficient to deliver the hot lean mixture necessary for maximum economy at moderate loads. It will be seen that the dilution in case both sets of ports are 85 completely in register will be much greater than this so that the mixture may easily be diluted to a point where it will not ignite, or at least it will become so weak and be so hot that even without any load the engine 90 will be unable to develop such excessive speed as to injure itself.

Without further elaboration, the foregoing will so fully explain the gist of this invention that others can, by applying 100 current knowledge, readily adapt it for various applications without omitting certain features that, from the standpoint of the prior art, apparently constitute the essential characters of the generic aspects of this 105 invention, and therefore such adaptations should and are intended to be comprehended within the meaning and range of equivalency of the following claims.

I claim as my invention:

1. In combination with an internal combustion engine having an inlet manifold, an exhaust manifold and a carburetor, two valve means in series, one of said valve means tending to permit a flow of air increasing with increased throttle opening, and the other valve means tending to permit a flow of air increasing with increased vacuum in the inlet manifold, means for heating the air flowing through said valves, and means for delivering the heated air into the mixture from the carburetor, said first mentioned valve means permitting appreciable leakage at high vacuums.

2. In a device of the class described, an exhaust manifold, a chamber formed in said manifold and exposed to the heat of the exhaust gases, the corners of said chamber extending to points over the inlet ports of the engine, passageways from the corners of 120 125 130

said chamber into the inlet ports, and a centrally located air inlet for said chamber.

3. In a device of the class described, an exhaust manifold, a chamber in said manifold exposed to the heat of the exhaust gases, passageways from the ends of the chamber to the inlet ports of the engine, and a gasket overlying the chamber, said gasket having an air inlet located centrally between the 10 ends of the chamber.

4. In a device of the class described, a carburetor having a rotatable throttle, a tube having its axis coincident with the axis of the throttle, a rotatable sleeve on said tube, 15 means for rotating the sleeve and the throttle simultaneously, ports in the sleeve and in the tube adapted to be moved into register as the throttle opens, a resiliently held plunger inside the tube, ports in said plunger 20 and tube, and means for moving said plunger ports into register in proportion to the vacuum in the inlet passages.

5. In a device of the class described, an exhaust manifold, walls formed in said exhaust manifold defining a chamber therein exposed to the heat of the exhaust gases and open to the atmosphere, a gasket overlying said chamber and a cover overlying said gasket, said cover being arched to provide a 25 passageway between itself and the gasket, said gasket having an aperture centrally located between its ends and passageways from opposite ends of the chamber to the inlet ports of the engine.

35 6. In a device of the class described, an exhaust manifold, walls formed in said exhaust manifold defining a chamber therein exposed to the heat of the exhaust gases and open to the atmosphere, a gasket overlying said chamber, and a cover overlying said gasket, said cover being arched to provide a 40 passageway between itself and the gasket.

7. In a device of the class described, an

exhaust manifold, walls formed in said exhaust manifold defining a chamber therein 45 exposed to the heat of the exhaust gases and open to the atmosphere, a gasket overlying said chamber, and a cover overlying said gasket, said cover being arched to provide a passageway between itself and the gasket, 50 said gasket having an aperture located midway between its ends and said cover having an aperture located without reference to the location of the aperture in the gasket.

8. In a device of the class described, an 55 exhaust manifold and an inlet manifold, means associated with said exhaust manifold and deriving heat therefrom for delivering heated dilution air into the mixture supplied to the engine, and a plurality of valve means in series controlling the supply of heated dilution air, the dilution air passing first through said valve means in a cold condition and subsequently through said heating means.

65 9. In a device of the class described, an exhaust manifold having apertured bosses extending down over the inlet ports of the engine to define short passageways communicating with the inlet ports, a chamber 70 housed in said exhaust manifold and exposed to the heat of the exhaust gases, and passageways from said chamber opening into the passageways in said bosses.

10. In a device of the class described, an 75 exhaust manifold having a separate chamber formed in it, said chamber being exposed to the heat of the exhaust gases, an air inlet to said chamber, and passageways from the chamber to said inlet ports of the engine, the 80 paths from said air inlet to the inlet ports being substantially equal.

In testimony whereof, I have hereunto set my hand.

IRVEN H. WILSEY.
